(57) **CLAIM**

The ornamental design for an “exercise device for cradling the head for situps,” as shown and described.

DESCRIPTION

FIG. 1 is a top plan view of an exercise device for cradling the head for situps, showing my new design;

FIG. 2 is a front elevation view thereof;

FIG. 3 is a perspective view thereof;

FIG. 4 is a top plan view of an alternate embodiment of the exercise device for cradling the head for situps;

FIG. 5 is a front elevation view thereof; and,

FIG. 6 is a perspective view thereof.
